7 Claims. (Cl. 333—7)

The present invention relates to microwave switching or commutating techniques.

The problem of switching microwave energy between two channels is often encountered in radar and radio links techniques, in particular where waveguides are used.

In many cases, an extremely rapid commutation of substantial energy amounts is desired. This is, in particular, true for radar systems.

Many systems have been proposed to this end, and among them the ferrite switches. However, ferrite switches are generally not stable because of the losses due to temperature increases when high energy amounts are involved. Besides, substantial energy is required for controlling such switches.

Σ junctions, whose branches include resonators, within which plasma is created by means of an external voltage are also known. This plasma detunes the resonator and thus modifies the transfer characteristics.

However, such plasma switches have substantial drawbacks:

(a) The passband is limited by the high Q factor of the resonators.

(b) The adjustment of the rate of ionization of the plasma sets difficult problems. If it is too high, the microwave field may, by itself, initiate the formation of plasma, without any control voltage being applied, this being due to the ultra-high frequency energy concentration in the resonator.

(c) If the rate of ionization is too low, the detuning upon plasma formation may be too low.

It is an object of this invention to provide a microwave plasma switch free from such troubles. In the plasma switch of the invention, the gas, which is ionized into plasma, is at a very low pressure, say of order of 0.1 mm. Hg, so that no ionization is possible under the action of the ultra-high frequency field alone. Besides, the housing in which plasma is formed is placed where the microwave field intensity is low and the formation of plasma modifies to an appreciable degree the electromagnetic field outside of the area where it is created by means of a low frequency control voltage.

The wave that propagates through the area, where plasma is formed, may be, for example, a travelling wave.

The invention will be better understood from the following specification and appended drawings wherein:

FIGS. 1 and 2 show in perspective phase shifting structures to form microwave switches according to the invention;

FIGS. 3 and 4 are diagrammatic views of switches according to the invention;

FIG. 5 is an explanatory diagram; and

FIGS. 6 to 10 show further embodiments of the invention.

2

Referring to FIG. 1, there is shown a rectangular waveguide 1, within which a travelling wave propagates. Along one of the small sides of guide 1 is placed a curved bulb 2, for example of glass, filled with a very low pressure gas, for example 10^{-4} Torr.

At the ends of bulb 2 are respectively placed electrodes 3 and 4, between which an A.-C. supply 5 establishes a low frequency sinusoidal field at predetermined instants.

The unit operates as follows:

A high energy wave propagates along the guide. The gas within bulb 2 being at a low pressure, this energy cannot by itself initiate plasma formation. As long as said gas is not ionized, bulb 2 does not have any appreciable effect on wave propagation, its reactive impedance being low.

When A.-C. voltage is applied to electrodes 3 and 4, the gas is ionized into plasma and becomes conductive. It is then as though the guide side wall were moved to match the inner wall of bulb 2. This brings about an additional phase-shift in the wave propagation along guide 1. Thus, when no voltage is applied to electrodes 3 and 4, bulb 2 behaves as a good dielectric. During the time intervals when voltage is applied to electrodes 3 and 4, the plasma filled bulb 2 behaves as a perfect reflector. The effect is the same as if the waveguide wall were set off by a maximum distance Δa .

The phase-shift thus brought about can be expressed as:

$$\Delta\varphi = \Delta k_g l$$

where l stands for the waveguide length, along which the obstacle thus created extends, and Δk_g is the variation of the wave number

$$k_g = \frac{2\pi}{\lambda_g}$$

in the guide, λ_g being the operating wave length in the guide.

Δk_g can be written:

$$\Delta k_g = \frac{\Delta a}{\sqrt{k_o^2 - \left(\frac{\pi}{a}\right)^2 a^3}} \frac{\pi^2}{a^3}$$

where Δa represents the above mentioned guide wall transversal displacement,

$$k_o = \frac{2\pi}{\lambda_o}$$

the wave number in free space, and a is the width of the guide.

To obtain a phase shift $\Delta\varphi = \pi$, taking λ_o as unity and writing:

$$\frac{l}{\lambda_o} = l'; \frac{a}{\lambda_o} = a'; \frac{\Delta a}{\lambda_o} = \Delta a'$$

one has:

$$l' \frac{\Delta a'}{a'} = a' \sqrt{4a'^2 - 1}$$

If it is desired that the phase shifting structure may operate within a 10% frequency band, one may take a cut off wavelength $\lambda_c = 2a = 1.15\lambda_o$.

For

$$\frac{\Delta a}{a} = \frac{1}{10}$$

and since

$$\frac{\lambda_g}{\lambda_0} = 2.025$$

the above formula gives: $l = 1.5\lambda_g$.

FIG. 2 shows a further embodiment of the invention. Instead of bulb 2 of FIG. 1, a plurality of tubes 21 are inserted along the waveguide lateral wall. Electrodes 30 and 40 are provided at the upper and lower ends of tubes 21.

The entire length of the waveguide portion, where phase shifting elements 21 are placed, is, for example, $1.5\lambda_g$, the number of bulbs being for example about 40. The bulbs are equispaced and fed in parallel, each of them furnishing a phaseshift of the order of 10%. The total phaseshift is of the order of 360° .

The switch shown in FIG. 3 comprises two phase-shifters 101 and 102 according to the invention.

Phaseshifters 101 and 102 are placed in branches I and II of a magic tee 4, having output branches III and IV. According to whether they are excited or not, phaseshifters 101 and 102 provide a π or 0 phaseshift. The structure being symmetrical, the propagations through the two channels are either in phase or 180° out of phase. As is well known, the output energy flows through branch III or branch IV as the case may be.

FIG. 4 shows a further switch. Phaseshifters 101 and 102 are placed in the two input arms 1a and 1b of a 3 db hybrid junction J. the control inputs aa' and bb' of phaseshifters 101 and 102 are coupled to a square wave voltage generator, which provides at its outputs, at aa' and bb' respectively, the waves shown in FIG. 5. These waveforms have a period of T and are out of phase by $T/2$. The maximum voltage U_0 is adjusted so that each phaseshifter will give a $\pi/2$ phaseshift. Under these conditions, when phaseshifter 101 is energized, energy is collected at the output arm 23. When phaseshifter 102 is energized, energy is collected at the output arm 22.

The arrangement has the following advantages:

- (a) Phaseshifts by only $\pi/2$ may be used, which involves lower losses;
- (b) The arrangement is perfectly symmetrical.

The losses are negligible compared to the "switching coefficient" (fraction of the energy appearing in the arm when no energy is wanted).

FIGS. 6, 7 and 8 show further embodiments of the invention.

In the switch portion of FIG. 6, the bulb has a rectangular cross section. The two broad walls 201 and 202 having a convex cylindrical shape extending within the waveguide. Upper and lower walls 203 and 204 are metalized and control electrodes 303 and 304 are soldered thereto.

In the embodiment of FIG. 7, the phaseshifting bulb is identical to that of FIG. 6, but guide 1 has in wall 10, facing the bulb, a bulge, the maximum lateral dimension of which is Δ_a . This arrangement results in that the loss is the same, whether the bulb is triggered, or not.

In the switch portion shown in FIG. 8 two enclosures 20 and 21 are provided all along the adjacent walls 10 and 11 of guide 1. Enclosures 20 and 21 are controlled by four electrodes 303, 304 and 305, 306. The formation of plasma results in a restriction of the useful guide section by $\Delta_a/2$ along each lateral wall.

FIG. 9 is a top view of a still further embodiment. Bulb 2 is identical to that of FIG. 7, for example. However, on the lateral wall 10 is placed a dissipative body 100, which causes an attenuation substantially equal to the attenuation which occurs in the ionized plasma filling tube 2.

FIG. 10 is still another embodiment, incorporating a total coupling hybrid junction. The latter comprises three branches: an input branch 1001 and two output branches 1002 and 1003.

Enough windows 1005 are placed between adjacent branches arms 1002 and 1003 for the whole of the energy to pass, by coupling, from branch 1001 into branch 1003. A plasma tube 1006 of cylindrical shape and symmetrical with respect to the wall common to branches 1002 and 1003, is excited by electrodes 1007 and 1008 connected to an A.-C. power supply.

When this tube is energized, everything happens as though there were no windows, and energy is confined to branch 1002. In the opposite case, as indicated above, there is total coupling and transfer of energy between branches 1002 and 1003.

The A.-C. power source can be of any known type say a Ruhmkorff coil, for example.

The present invention is of course not limited to the arrangements shown, which were given only by way of example. Generally speaking, the invention provides a microwave switch comprising microwave phaseshifters or similar devices incorporating a low pressure gas containing enclosure, the plasma formation being caused by a low frequency field and resulting in a modification of the electric field outside said enclosure.

What is claimed, is:

1. A phaseshifting structure for a switch for switching 25 microwave energy from one channel to another comprising: at least one rectangular waveguide, having two small sides and two large sides; near one of said small sides, a curved bulb filled with a low pressure gas, said bulb having two ends and extending from one of said small 30 sides; into said guide; two electrodes respectively positioned at said two ends; and means for feeding to said two electrodes a low frequency alternating voltage; said one small side having between said two ends a curved projection towards outside.

2. A phaseshifting structure for a switch for switching 35 ultra-high frequency energy from one channel to another comprising: at least one rectangular waveguide having two small sides, a plurality of equispaced rod shaped containers filled with a low pressure gas against one of said 40 small sides, each of said containers having two ends; respective electrodes positioned at said ends; and means for feeding a low frequency alternating voltage to said two electrodes.

3. A phaseshifting structure for a switch for switching 45 microwave energy from one channel to another comprising: at least one rectangular waveguide having two small sides and two large sides; a bent bulb extending from one of said small sides into said guide and filled with a low pressure gas, said bulb having two conductive surfaces in 50 said large sides respectively, and means for feeding to said conductive surfaces an alternating voltage having a frequency low with respect to the frequency of said microwave energy.

4. A phaseshifting structure for a switch for switching 55 microwave energy from one channel to another comprising: at least one rectangular waveguide having two small sides and two large sides, against each of said small sides, two enclosures filled with a low pressure gas extending parallel thereto from one large side to the other, two 60 electrodes in each of said enclosures, and means for feeding to said electrodes an A.-C. potential having a frequency low with respect to the frequency of said microwave wave energy.

5. A switch for switching microwave energy from one 65 channel to another, comprising two identical rectangular waveguides, having respectively two large sides and two small sides, one of said small sides being common to said guides, coupling windows equispaced in said common side, a container enclosing said coupling windows, said 70 container being filled with a low pressure gas, two electrodes connected to said containers; and means for feeding to said two electrodes an alternating potential having a frequency low with respect to the frequency of said energy.

6. A switch for switching microwave energy from one channel to another comprising two waveguides having a common input and respective outputs; in each of said guides, outside the region in which the greatest part of energy is concentrated, a container filled with a low pressure gas; means for ionizing said gas selectively in at least one of said containers; and a magic tee having two input arms, respectively coupled to said outputs, and two output arms.

7. A switch according to claim 6, wherein said ionizing means ionize said gas in both containers. 10
